UNITED STATES PATENT OFFICE

2,507,393

THERAPEUTIC APPARATUS

Roy B. Wiprud, Duluth, Minn.

Application August 4, 1948, Serial No. 42,430

3 Claims. (Cl. 219—39)

1

This invention relates to therapeutical apparatus of the kind adapted for administration of gases such as oxygen and the like, particularly to the treatment by dentists of the gums.

It is often desirable to introduce oxygen by the dentist in the treatment of the gums. Oxygen is normally stored under high pressure and at normal temperatures. When the oxygen is to be used, it is withdrawn from the high pressure source and reduced in pressure so as to enable proper administration by the dentist. In the reduction of the pressure the temperature of the oxygen is lowered to a point that it is generally uncomfortable for the patient. It is an object of this invention to correct this situation so that a proper administration of oxygen to the gums can be carried out at a temperature which is comfortable to the patient.

A further object of the invention is to provide a novel, compact apparatus of simple and economical construction which may be easily transported and used in the administration of gases and liquids.

A selected embodiment of the invention is illustrated in the accompanying drawings, wherein:

Figure 1 is a perspective view of the apparatus;

Figure 2 is a sectional view through the apparatus; and

Figure 3 is a sectional view through the bottom cover plate and one type of heater. This device shown in the drawings may be used for several purposes as for heating a liquid or a gas but is generally designed for the heating of oxygen primarily used by dentists in the therapeutical application of oxygen to the patient. The gas is stored in a suitable high pressure storage vessel and is fed to the apparatus through tube or conduit 20. Generally located between the high pressure source and the tube 20 is a pressure reducing valve in which the pressure of the oxygen is lowered and as the pressure of the oxygen is lowered the temperature also is lowered. The oxygen as it passes through the tube 20 is heated to about body temperature and this will result in an application which is comfortable to the patient. 10 is a metal block having high heat conducting characteristics and it may be cast in the form of a hollow block with a central opening 12 or it may be cast in various shapes such as cylindrical, it being understood that the shape of the block 10 can be changed without departing from the scope of the invention. The gas or liquid carrying tube is disposed helically about the block and imbedded in the metal block. The tube should be metal having high heat conducting

2

characteristic. Copper tubing would be satisfactory in this connection. Due to the arrangement, the oxygen being discharged through the conduit 24 is of substantial constant temperature and of a temperature which is comfortable to the patient being treated. The opening 12 is closed at top and bottom by plate members 14 and 18 respectively. These tops are secured to the metal block by any suitable means such as screws 16. Secured to the bottom cover 18 is heating element 26 which receives its current from a suitable source (not shown) by way of conductors 27 which run directly to the heater and thence to a thermostat 30 and then back to the source to conductor 28. Conductors 27 and 28 extend through the metal member 10 through suitable openings which is so arranged that the heat from the block is not dissipated. It is to be understood that any suitable type of heater may be employed and for the purpose of illustration a heater is shown in Figure 3 which consists of insulating member 34, resistance units 36 and the heating unit is supported in a suitable member carried by the plate bottom 18 and is secured thereto by suitable means such as screws 32.

In operation, the conductors 27 and 28 are connected to a suitable source of electrical energy and the thermostat 30 allows current to flow to the heating element 26 to raise the temperature of the metal mass and thereby raise the temperature of the oxygen. When the metal mass 10 is brought to the desired temperature the contacts of the thermostat 30 will open and stop the flow of current to the heater. The gas being heated enters through the tubing 20 and flows through the tubing imbedded in the metal mass. The metal mass having high heat conducting characteristics will instantly transmit heat to the tube and consequently raise the temperature of the oxygen. When the heat is transmitted to the gas the temperature of the metal mass will be lowered which will cause the thermostat 30 to close the electrical contact and thus the heating element 26 restores the heat to the metal mass, thus restoring heat lost to the gas. There is a time interval between the introduction of the gas at 20 and the response of the thermostat 30 and the heating unit 26. This requires the metal mass 10 to be large enough so that the heat removed by the gas will not lower the temperature of the metal mass beyond definite allowable limits before the electrical heating units starts to restore the heat. It is important that the heating unit should be sufficient capacity to restore the heat to the metal

mass faster than the gas can remove the heat therefrom.

The thermostat is so arranged that it is responsive to the change of temperature at the metal mass. It is to be understood that the arrangement of the heater 26 as shown in Figure 1 is important as it produces the most efficient operation of the apparatus.

The invention broadly consists of four principal elements: a metal block to store and conduct heat; a tube or pipe in which the gas is contained and heated; a heating element; and a thermostat. The metal block can be cast in any form and in fact can be cast without central opening. The gas carrying tube can be any shape as long as it is cast integral with the metal block. The thermostat could be placed in any position on the metal block as the metal has high heat conducting properties and the temperature of the entire mass will be approximately the same temperature.

What is claimed is:

1. An apparatus of the class described comprising a substantially rectangular metal member having a centrally disposed opening, a metal tube having high heat conducting characteristics disposed in the metal member, a thermostat mounted in the centrally disposed opening and responsive to the change in temperature of the metal mass, top and bottom cover members, and a heating unit mounted on the bottom cover member and extending into the centrally disposed opening, said heating unit of a size to occupy only a small portion of the centrally disposed opening.

2. An apparatus of the class described consisting of a substantially rectangular metal mass having a centrally disposed opening therein, said metal mass having high heat conducting characteristics, a tube disposed within the metal mass, a thermostat mounted within the centrally dis-

posed opening and responsive to changes in temperature of the metal mass, a removable plate secured to the metal mass for covering the top of the centrally disposed opening, a removable plate secured to the metal mass for covering the bottom of the centrally disposed opening, a heater removably secured to the bottom plate and extending into the centrally disposed opening.

3. An apparatus of the class described consisting of a metal mass having a centrally disposed opening therein, said metal mass having high heat conducting characteristics, a tube having high heat conducting characteristics disposed within the metal mass, a thermostat mounted on the metal mass and responsive to changes in temperature of said mass, a cover secured to the metal mass for closing one end of the centrally disposed opening, a plate removably secured to the other end for closing the other end of the centrally disposed opening, an electrical heating means secured to the said plate and extending into the centrally disposed opening, said heating unit of a size to occupy only a small portion of the centrally disposed opening.
